UNITED STATES PATENT OFFICE

144,014

DESIGN FOR AN EMBROIDERED FABRIC

Anton Walter, New York, N. Y.

Application October 19, 1945, Serial No. 123,013

Term of patent 3½ years

(Cl. D92—1)

To all whom it may concern:

Be it known that I, Anton Walter, a citizen of the United States of America, residing in New York city, county of New York, and State of New York, have invented a new, original, and ornamental Design for an Embroidered Fabric, of which the following is a specification, reference being had to the accompanying drawing, forming part thereof, wherein the figure is a plan view

of a piece of embroidered fabric showing my new design. The dotted lines outline a design unit, which unit is repeated throughout the fabric as indicated by the extensions beyond the unit boundary.

I claim:

The ornamental design for an embroidered fabric, substantially as shown and described.

ANTON WALTER.
